Primary Examiner—Theodore M. Shooman*Assistant Examiner*—Cheri Cohen*Attorney, Agent, or Firm*—Dick and Harris[57] **CLAIM**

The ornamental design for a portable dispenser for generally spherical confectionerries, as shown and described.

DESCRIPTION

FIG. 1 is a perspective view of the portable dispenser for generally spherical confectionerries showing our new design;

FIG. 2 is an enlarged front elevational view thereof;

FIG. 3 is a rear elevational view of FIG. 2;

FIG. 4 is a left side elevational view of FIG. 2, the unshown opposite side being a mirror image;

FIG. 5 is a top plan view of FIG. 2; and,

FIG. 6 is a bottom plan view of FIG. 2.

The broken line showing of a head in FIG. 1 is for illustrative purposes only and forms no part of the claimed design.
